UNITED STATES PATENT OFFICE.

AUGUST ERIC PEARSON, OF TORONTO, ONTARIO, CANADA.

BABBITTING MACHINE.

Application filed November 26, 1921. Serial No. 517,938.

To all whom it may concern:

Be it known that I, AUGUST ERIC PEARSON, a citizen of the United States of America, and a resident of the city of Toronto, in the 5 county of York, in the Province of Ontario, Canada, have invented certain new and useful Improvements in Babbittting Machines, of which the following is the specification.

My invention relates to improvements in 10 babbittting machines, and the object of the invention is to devise a simple device for babbittting such articles as bearing caps and such as may be readily adaptable for pouring the metal under varying conditions, and 15 it consists essentially of the arrangement and construction of parts as hereinafter more particularly explained.

Fig. 1 is a front elevation of my babbittting machine.

20 Fig. 2 is a plan view of my machine.

Fig. 3 is a side elevation of my machine.

Fig. 4 is a front elevation of the base casting, and swinging support carried by the base casting.

25 Fig. 5 is a plan sectional view, the left hand side showing the cap to be babbittted in position, and the right hand side of the view showing the parts with the cap removed.

Fig. 6 is a cross sectional view through 30 Fig. 1, taken on line 6—6 and looking in the direction of arrow.

Fig. 7 is an enlarged sectional detail through the bearing cap, mandril and end blocks showing the babbitt poured into the 35 cap.

In the drawings like characters of reference indicate corresponding parts in each figure.

1 indicates the base casting which 40 comprises a base piece 2 from which extend vertical standards 3 and 4. At the top of these standards is located an orifice 5. 6 is an arm extending rearwardly from each standard 3 and 4, such arm being provided 45 with a slot 7, the arm and slot being curved concentrically to the centre of the orifice 5.

8 is a mandril supporting member which 50 comprises a base plate 9 in which is located the recess 10 forming the bed for the mandril as hereinafter described, and with side guides 11 for a purpose which will hereinafter appear.

The mandril supporting member also comprises lugs 12 which extend upward from 55 each side of the base plate 9 at the inside of

each standard 3 and 4. The lugs 12 are also provided with orifices 13 through which and each orifice 5 extends a bolt 14 thereby pivotally supporting the mandril base upon the standards 3 and 4. 15 are arms which extend from the base plate 9 at each side thereof closely adjacent to the arms 6 and similar in form to such arms.

16 are wing nuts which are screwed into orifices formed in the arms 15 and extend 65 through the slot 7 so as to clamp each pair of arms 15 and 6 together.

The base plate 9 is also provided with a pair of horizontally disposed lugs 17 and 18, a pair of lugs 17 and 18 being disposed at 70 each side of the base plate 9. Each portion of the mandril support forming the guide ways 11 is cut away intermediately of its length as indicated at 19, see Fig. 4, so as to leave an opening 20 located between the 75 base plate 9 and each standard 3 and 4.

21 are arms which are swung between the lugs 17 and 18, the free ends of the arms extending at right angles to the body of the arm and through a corresponding opening 80 20. 22 is the mandril base which fits in the recess 10 and is secured therein by screws 23 extending through the back of the mandril support 9. 24 is the mandril proper which is in the form of a semi-cylindrical body secured to, or formed integral with the base 22. 25 is a groove formed in the outer face of the mandril 24 at its upper end, the upper portion being flared outward as indicated at 26 so as to receive the molten babbitt 90 which is poured into the groove.

28 is a bearing cap of usual construction provided with the bosses 29 having bolt orifices 30. 31 are orifices formed in the mandril base 22 in a line with the orifices 30. 95 The bearing cap 28 fits around the mandril 24 so as to leave a space to receive the babbitt.

32 and 33 are blocks which are similar in form to the bearing cap 28 but considerably 100 larger in diameter. The outwardly extending flanges 34 and 35 of these blocks fit slidably into the guide ways 11 and bear against the ends of the cap 28.

36 and 37 are semi-circular recesses formed 105 in the blocks 32 and 33 into which the babbitt enters when poured so as to form what is known as the "fillet".

36^x and 37^x are semi-circular grooves formed concentric to the aforesaid recesses 110

36 and 37. The inner edge of each groove is substantially flush with the outer diameter of the bearing cap 28.

These grooves are filled with a fibrous 5 substance such as asbestos wool, this wool overhanging the division between the cap 28 and the blocks 32 and 33 so as to prevent the leakage of babbitt.

38 and 39 are rods each of which are provided at one end with a handle 40 and at its 10 opposite or inner end with an inturned portion 41 which passes through the orifices 30 and 31. The inturned portion 41 is provided with an enlargement 42 which bears 15 against the top of the boss 29 of the cap 28.

43 and 44 are levers which are pivotally carried upon the ends of the turned portions of the arms 21. The inner or operative ends of the levers bear against the enlargements 20 42 and are located between the standards 4 and 5 and the rods 38 and 39.

45 are levers pivoted between the lugs 46 carried by the mandril support 8. The handle of each of these levers is spring held outward by a spiral spring 47. The opposite ends of the levers 45 extend in the operative position over the rods 38 and 39 to lock the inturned ends of the rods in the orifices 30 and 31.

30 The mandril support 8 is provided with a foot plate 48 from which extend hollow bosses 49 and 50 in which are held spiral springs 51. The springs 51 bear against the lower end of the block 33 forming a support 35 for the same.

52 is a pull rod which extends through an orifice formed in the foot plate 48 and is secured at its upper end in the block 33. The pull rod 52 is operated either manually or by 40 any other suitable form of foot mechanism.

Having described the principal parts involved in my invention, I will briefly describe the operation of the same.

When it is desired to babbitt a cap, the 45 block 32 is lifted upward so that the flanges 34 slide out of the guide ways 11, thereby removing the block.

After this has been done, the wing nuts 16 are loosened and the mandril support swung 50 to a horizontal position, the wing nuts being then again tightened so as to hold the mandril 24 and its support in a horizontal position ready to receive a bearing cap. As the mandril support is swung to a horizontal 55 position the arms 21 are freed so that they swing outward upon their pivot carrying the levers 43 and 44 outward and downward clear of the mandril and its support.

In order to place the cap 28 in position, the 60 rods 38 and 39 are inserted in the orifices 30 of the cap, and the cap lifted by means of the rods 38 and 39 into position upon the upper end of the block 33 so as to fit around the mandril 24 and against the outer face of the 65 base 22.

After this has been done the rods 38 and 39 are swung beneath the operative ends of the levers 45. It will be noted that each of the levers 45 is provided with a curved outer end 45^x. As the rods 38 and 39 are swung beneath the levers 45 they engage the curved portions 45^x so as to force the levers 45 outward against the pressure of the springs 47 as the rods 38 and 39 enter beneath the levers. 70

The block 32 is then replaced and the 75 grooves 36^x and 37^x filled with asbestos fibre so as to pack the joints between the blocks 32 and 33 and the cap 28. If the cap 28 is provided with oil holes or like orifices, the babbitt may be poured through these when the cap is in the horizontal position above described. If however it is necessary to pour the babbitt into the cap endwise, the wing nuts 16 are again released and the 80 mandril support swung either to a vertical position or an angular position, the angle being decided upon according to the conditions and by actual test.

When the cap has been placed in position as before described, the molten babbitt is 90 then poured into the groove 25 flowing from thence into space between the cap and the mandril and into the recesses 36 and 37.

In order to remove the cap after it has 95 been babbitted, the block 32 is first removed, then the rods 38 and 39, the block 33 forced downward and the levers 43 and 44 brought into engagement with the enlargement 42, or in the position shown in Fig. 1. These 100 levers are then forced downward at their outer ends serving to kick the cap out of position and clear of the device. The rods 38 and 39 are then reinserted in the cap orifices to form means for manually lifting the hot cap to the desired location. 105

Although I have described the withdrawal of the block 33 as applied to the operation when the mandril is set at a vertical or angular position, it is more applicable for use when the mandril is in a horizontal position 110 as it is then necessary to withdraw the block 33 so as to carry the lower fillet out of the recess 37 before the cap can be lifted.

From this description it will be seen that I have devised a very simple form of babbitting machine which is adaptable for use under all circumstances and conditions found in babbitting of caps and like articles. 115

What I claim as my invention is:

1. In a babbitting machine, a mandril supported upon a suitable structure, guideways located in each side of the mandril, a resiliently supported lower block engaging the lower end of the mandril and slidable within the guideways, an upper block also freely 120 slidable within the guideways and resting upon the upper end of the bearing cap, and a lever support for the cap adapted to eject the cap and upper block from the guideways 125 when the lower block is withdrawn against 130

the pressure of the resilient supporting means.

2. A babbetting machine comprising a base forming a mandril support, a semi-cylindrical mandril carried by the base, guide ways located at each side of the mandril, a block slidably held in the guide ways and adapted to bear against each end of the cap when in position surrounding the mandril, a pair of rods each having an inturned end adapted to fit into a bolt orifice of the cap, a pivoted spring pressed lever, having an outturned end pivotally carried upon the mandril support and adapted to extend over the rods when in their operative position.

3. A babbetting machine comprising a base provided with side standards having bearing orifices at their upper ends and arms extending from the standards and having slots therein concentric with the centres of each orifice, a mandril support provided with lugs, pivot bolts extending through the orifices of the standards and the lugs, arms car-

ried by the mandril support, a locking bolt extending through each of the aforesaid slots into the arms of the mandril support, a semi-cylindrical mandril carried by the support having a babbitt pouring groove at its upper end, guide ways located at each side of the mandril support, blocks slidably carried in the guide ways and adapted to bear against each end of the cap when in position around the mandril, swinging arms carried by the mandril support at each side, ejecting levers carried by the arms, rods having inturned ends entering the bolt orifices of the cap and each having an enlargement bearing against the corresponding boss of the cap, and against which the operative ends of the levers are adapted to bear, a spring pressed locking lever carried by the mandril support and extending over each rod, and a yieldable support over the lowermost block.

AUGUST ERIC PEARSON.
